UNITED STATES PATENT OFFICE.

WINFIELD S. SHANAHAN, OF EAST CHATHAM, NEW YORK, ASSIGNOR OF
TWO-THIRDS TO SYLVESTER C. HULBERT, OF SAME PLACE, AND MONT
G. CURTIS, OF TROY, NEW YORK.

THILL-COUPING.

SPECIFICATION forming part of Letters Patent No. 295,440, dated March 18, 1884.

Application filed January 14, 1884. (No model.)

To all whom it may concern:

Be it known that I, WINFIELD S. SHANAHAN, a citizen of the United States, residing at East Chatham, in the county of Columbia and State of New York, have invented certain new and useful Improvements in Thill-Couplings, of which the following is a specification, reference being had therein to the accompanying drawings.

10 My invention relates to anti-rattlers for shaft-couplings for vehicles; and the object I have in view is to provide a double spring in the eye of the clip, for the purpose of more effectually preventing rattle and wear without materially increasing the cost of the device.

15 In the accompanying drawings, which make a part of this specification, Figure 1 represents partly a side and partly a sectional view of my invention, and Fig. 2 a detached perspective view of the spring in its normal position.

20 In the figures, A represents a clip, by means of and through which the shaft-irons of a vehicle are connected to the shafts of same. D represents an enlargement on one side of the clip, in which is formed an eye or annular opening, to receive the anti-rattler and the end of the shaft-iron. This enlargement is provided with an opening to receive a cross-bar 25 on the end of the shaft-iron.

25 B represents the shaft-iron; C, the bar upon it, which is situated between two wings, B', which embrace the enlargement D on two sides when the parts are together and in working position.

30 E represents a block of rubber, which is

fitted in the eye of the enlargement D after having been surrounded with a spring metallic band, F. This block E is provided with a rectangular opening, a, and the metallic spring + 40 F, after surrounding the said block, has its ends inserted in said opening a, and reaching to its bottom, as represented. The spring F is made larger than the eye, and is compressed in order to enter the same. After entering, 45 its ends press against the sides of the opening in the block E, and assist in expanding it and keeping it tight in the eye. The shaft is raised to allow the bar C to enter the opening a. When it is lowered, the bar is caught and 50 secured in the block E, as is usual in this class of coupling devices.

What I claim as new, and desire to secure by Letters Patent, is—

1. The block E, formed of any suitable elastic substance, and surrounded by a metallic spring, F, in combination with an axle-clip and shaft-iron of a vehicle, the several parts being constructed substantially as and for the purpose set forth. 55

2. The block E, provided with a rectangular opening, a, and surrounded with a metallic spring, the ends of which project into the said opening for the purpose of keeping the block distended, substantially as specified. 60 65

In testimony whereof I affix my signature in presence of two witnesses.

WINFIELD S. SHANAHAN.
